Inventor:
Louis C. Baldwin.

UNITED STATES PATENT OFFICE

LOUIS C. BALDWIN, OF CHICAGO, ILLINOIS

COMBINATION KEY AND COIN CONTAINER

Application filed October 26, 1931. Serial No. 571,149.

This invention relates to a combined coin and key case and it pertains more particularly to a flexible key container provided with a pocket with a flexible closure.

5 The object of my invention is to adapt a key case for carrying small coins so that it may serve the double purpose of a key case and a coin container. A further object is to provide a device of this kind with a flexible closure which is tight enough to prevent the escape of extremely small objects. A further object is to minimize the bulk of the device and to avoid the use of extra flaps. A further object is to provide a closure at the edge of 10 the back panel of the key case so that the closing means will be between the edge of the case and the key, and so that one side of the key container may be used in conjunction with the coin case to facilitate the selection 15 of the desired coin therefrom. Other objects 20 of the invention proceed.

In practicing my invention I fasten a flexible sheet to the back panel of the key case, 25 preferably by sewing it on three sides and leaving the fourth side, adjacent to the right hand flap, unsecured. Along this unsecured edge I secure what is commonly called a zipper fastener which may be described as a 30 body having a slit member, connecting members on the edges of the slit, and means movable on said edges between the ends of the slit for controlling said members to open and close the slit. The particular structure and 35 the advantages which are accomplished thereby will be more apparent from the following description of a preferred embodiment.

In the accompanying drawing, wherein 40 similar parts are designated by like reference characters throughout the several views—

Figure 1 is a top plan view of my device with the key container open and the coin pocket closed.

45 Figure 2 is a similar view with the key container closed by one flap and with the coin pocket open to discharge its contents on the other flap of the key container.

50 Figure 3 is a cross section showing both the key container and coin pocket in closed position.

The container is preferably made of flexible leather, since it is one of the objects of my invention that it should conform as nearly as possible to the contents thereof and to the user's pocket. The key container consists of a back panel 10, a right flap 11 and a left flap 12. The left flap may be provided with a ball 13 of a snap fastener adapted to snap in fastener socket 14 to hold the key container in closed position. The keys 15 may be mounted on supports 16 which are pivotally mounted on hinges 17, which turn on rod 18 carried by metal back 19 which may be secured to the back panel of the key container by rivets 20 or by any other suitable means. It should be noted that the keys are pivoted to move in all directions. The hinged members normally fill the top of the case and the keys normally fill the center, thus leaving the bottom of the case normally empty. In accordance with my invention I utilize this space in the bottom of the case to carry coins or other small articles, as will be hereinafter described.

On the inner side of the back panel 10 I secure a flexible sheet 11 preferably by sewing it along the upper, the lower and the left hand edges. The flexible sheet member extends only to the base of the metal backing for the key support or, as shown in the accompanying drawing, the flexible sheet may be substantially commensurate with the back panel and the key container may be secured to the flexible sheet instead of to the back panel.

In the opening formed by the right hand edge of the flexible sheet and the left hand edge of panel 11 I secure a zipper fastener 21, which may be described as a slip tape 22, having stringers 23 arranged parallel to each other on opposite sides of the slit, each stringer being provided with interlocking connecting members 24 which are engaged or disengaged by sliding member 25, which may be pulled upwards or downwards by tab 26. The braid may be sewed or otherwise secured to the right edge of the inner sheet and to the adjacent portion of the key container, as shown in the drawing, so that when the tab 26 is pulled to its lower position the pocket between the

flexible sheet and the central panel will be closed (see Figure 1) and when it is pulled forwardly the pocket will be open (see Figure 2).

Coins or street car tokens 27 may be carried in this pocket or coin case in the same manner that they are carried in the ordinary purses or coin cases, and when it is desired to select a particular coin the tab 26 may 10 be moved upwardly to open the coin pocket and the contents of the case may be emptied onto flap 11. When the coin has been selected the remaining coins are slid back into the case by inclining flap 11 and tab 26 is pulled 15 downwardly. In the normal carrying position the coins occupy the lower part of the key container and thus utilize a space which has heretofore been wasted; the key mountings and hinges occupy the upper part of the case, the keys occupy the central part and the coins occupy the lower part. By means 20 of my flexible zipper fastener I avoid the possibility of the accidental opening of the pocket or coin case and I avoid the bulk of extra flaps.

While I have disclosed in detail a preferred embodiment of my invention it should be understood that I do not limit myself to the details hereinabove set forth. I contemplate the 30 use of other materials than leather, of other fastening means than sewing and of equivalent zipper fasteners. My invention is described by the following claims which should be construed as broadly as the prior art will 35 permit.

I claim:

1. An article of manufacture, comprising a 40 key container having a back and a flap adapted to fold over said back, means for mounting keys in said container, a sheet secured to said back by three edges to form a pocket, leaving the free edge adjacent the flap, a zipper fastener secured to the free edge of the sheet and to the adjacent part of the key container, and 45 means for opening and closing said flexible fastener whereby in its open position the flap may hold coins exposed to view and in its closed position the pocket may serve as a coin case.

50 2. An article of the class described, a key container comprising a back panel, a left flap and a right flap, means for pivotally mounting keys on said back panel, means for closing said key container by folding said left flap over said back portion and folding said right flap over said left flap, a sheet secured to said back at its upper and lower ends and adjacent one flap, a zipper fastener secured 55 to the container adjacent the other flap and to the unsecured edge of said sheet, means for opening and closing said fastener whereby in its closed position a tight, flexible closure is effected for the pocket between the 60 container and the sheet and in its open posi- 65

tion the contents of the pocket may be displayed upon the flap of the key container.

In witness whereof I have affixed my signature.

LOUIS C. BALDWIN.
